UNITED STATES PATENT OFFICE.

FREDERICK E. MUNSCHAUER, OF BUFFALO, NEW YORK, ASSIGNOR TO NIAGARA MACHINE & TOOL WORKS, OF BUFFALO, NEW YORK, A CORPORATION OF NEW YORK.

METAL-WORKING MACHINE.

Application filed August 8, 1927. Serial No. 211,406.

This invention relates to a sheet metal working machine for beading, edging, turning and wiring sheet metal in the manufacture of articles requiring such work.

5 It is the object of this invention to provide a machine of this character in which the gearing is completely enclosed in a solid casting so as to protect the same from dirt and also to prevent operators from getting their 10 fingers caught in the gearing and injured as frequently occurs in machinery of this type as heretofore constructed.

In the accompanying drawings:

Figure 1 is a vertical longitudinal section 15 of a sheet metal working machine embodying my improvements. Figure 2 is an end view of the same. Figure 3 is a vertical transverse section of the same taken on line 3—3, Fig. 1. Figures 4 and 5 are perspective views of 20 the casing of the machine viewed from opposite ends, respectively. Figure 6 is a fragmentary horizontal section, on a reduced scale, taken on line 6—6, Fig. 1.

Similar characters of reference indicate 25 like parts in the several figures of the drawings.

The enclosing casing of this machine forms the frame which supports the working parts and encloses some of them. This casing is made principally in one solid casting 30 and comprises a closed bottom 10 having a downwardly projecting boss 11 whereby the same is mounted on a support, a front wall 12 provided in its lower part with a fixed lower 35 front bearing 13 and a front opening 14 in its upper part, a rear wall 15 provided in its lower part with a fixed lower rear bearing 16, a closed top 17, and two side walls 18, 19, one of which has a side opening 20.

40 In the lower bearings is journaled a lower horizontal shaft 21 which extends lengthwise through the lower part of the casing and is held against lengthwise movement by a rearwardly facing shoulder 22 on the front 45 part of this shaft engaging with the front end of the lower front bearing and a collar 23 secured to the rear part of the lower shaft and engaging with the rear end of the lower rear bearing.

50 Within the upper front opening is arranged a vertically movable slide 24 which is provided with an upper front bearing 25 and on its opposite vertical edges with flanges 26 which engage with guideways 27

in the opposite vertical sides of the upper 55 front opening.

In the upper rear opening is arranged a sleeve 28 which is provided with a horizontal upper rear bearing 29. This sleeve is mounted on the casing so as to be capable of 60 turning about a horizontal transverse axis by means of transverse pivot screws 30 working in threaded openings 31 in the rear wall of the casing and engaging pivot seats in opposite sides of the sleeves 28. Clamping nuts 65 32 are applied to the pivot screws and bear against the outer side of the casing for holding the pivot screws in position after adjustment. In the upper front and rear bearings 70 an upper shaft 33 is journaled which extends through the upper part of the casing. These shafts are compelled to turn in unison by upper and lower intermeshing gear wheels 34, 35, which are arranged within the casing and are secured respectively to the upper and 75 lower shafts by pins 36, 37. The upper shaft is provided adjacent to its front end with a rearwardly facing shoulder 38 which bears against the front end of the upper front bearing.

80 On the front ends of the shafts outside of the casing are mounted co-operating rolls 39, 40, the peripheries of which may be of any suitable formation to produce beading, edging, turning or wiring on sheet metal for 85 various purposes. Although these rolls may be secured to the shafts in various ways it is preferable to employ the means shown in the drawings which consist of an externally threaded shank 41 on the front end of each 90 shaft engaging with an internally threaded opening 42 in the hub of the respective roll and a forwardly facing shoulder 43 on the shaft engaging with the rear end of said hub, and a clamping screw 44 working in a 95 threaded opening 45 in the front end of the shaft and having a head 46 at its front end which engages with the front end of the hub of the respective roll. The trend of the screw threads between the hub of each roll and its 100 shaft is in one direction and the trend of the screw threads between the screw 44 and this shaft is in the opposite direction; in other words, one is right and the other is left, whereby turning of each roll in either direction by means of its shaft will prevent this roll from becoming loose.

105 Turning of the rolls in either direction

may be effected by a crank handle 47 the hub of which may be secured to the rear end of either shaft depending upon whether the work in hand is to be moved forwardly or 5 backwardly through the rolls and also to suit other conditions.

Adjustment of the rolls lengthwise relatively to each other is preferably effected by a spring 48 surrounding the upper shaft and 10 engaging the rear side of the upper gear wheel and the front side of the bearing sleeve, and an adjusting screw nut 49 arranged on the threaded rear part of the upper shaft and engaging with the rear end of said sleeve. 15 Upon turning the nut 49 in one direction or the other the upper shaft will be moved lengthwise and thereby shift the upper roll relative to the lower roll for bringing the rolls into the proper relation. 20 Introduction of the gear wheels into the casing for mounting them on the shafts is effected through the side opening of the casing, which opening is normally closed by a cover or plate 50 secured to the casing over 25 the side opening by means of screws 51.

The rolls are moved toward and from each other to permit the introduction of sheets of metal therebetween as well as removal of the finished work by a spring 52 bearing at its 30 upper end against the underside of the slide and at its lower end against the lower end of the upper front opening in the front wall of the casing, and an adjusting screw 53 working in a threaded opening in the upper 35 front part of the casing and engaging with the upper side of said slide.

The sheet of metal to be operated upon is placed between the rolls while the latter are separated and this sheet is engaged with its 40 edge against a gage 54 in order to bring the same into the right place. This gage may be placed adjacent to the ends of the rolls and on either side of the same to suit to work in hand by mounting the same on a supporting rod 55 which is adapted to slide in either pair of openings 56 or 57 in the casing and held in position after adjustment by a set screw 58, as shown in Fig. 6.

In this machine the gearing is completely 50 enclosed so that no dirt can get to it to interfere with its operating or cause undue wear and normally the same can not be reached by the hands or fingers of the operator thereby preventing injury to the same.

55 I claim as my invention:

1. A metal working machine comprising an enclosing casing provided in the lower part of its front and rear walls with fixed bearings, a front opening in the upper part of its 60 front wall having vertical guideways on its opposite sides, a rear opening in the upper part of its rear wall, and a side opening in one of its side walls, a vertically movable slide arranged in said front opening and 65 guided in said ways and provided with an

upper front bearing, a sleeve arranged in said upper rear opening and provided with an upper rear bearing, pivots arranged on the rear wall and engaging opposite sides of said sleeve, a lower shaft journaled in said lower 70 bearings and extending through said casing, an upper shaft extending through said upper front and rear bearings and extending through said casing, upper and lower intermeshing gear wheels arranged within the 75 casing and secured to said upper and lower shafts, respectively; co-operating rolls mounted on the front ends of said shafts outside of said casing, a spring interposed between the underside of said slide and the 80 lower end of the front opening in the casing, an adjusting screw arranged in the upper front part of said casing and engaging with the upper end of said slide, a spring interposed between the rear side of said upper 85 gear wheel and the front end of said sleeve, a screw nut arranged on the rear end of said upper shaft and engaging with the rear end of said sleeve, and a cover secured to said casing over the side opening thereof. 90

2. A metal working machine comprising an enclosing casing provided in the lower part of its front and rear walls with fixed bearings, a front opening in the upper part of its front wall having vertical guideways 95 on its opposite sides, a rear opening in the upper part of its rear wall, and a side opening in one of its side walls, a vertically movable slide arranged in said front opening and guided in said ways and provided with 100 an upper front bearing, a sleeve arranged in said upper rear opening and provided with an upper rear bearing, pivots arranged on the rear wall and engaging opposite sides of said sleeve, a lower shaft journaled in said lower 105 bearings and extending through said casing, an upper shaft extending through said upper front and rear bearings and extending through said casing, upper and lower intermeshing gear wheels arranged within the 110 casing and secured to said upper and lower shafts, respectively; co-operating rolls mounted on the front ends of said shafts outside of said casing, a spring interposed between the underside of said slide and the 115 lower end of the front opening in the casing, an adjusting screw arranged in the upper front part of said casing and engaging with the upper end of said slide, a spring interposed between the rear side of said upper 120 gear wheel and the front end of said sleeve, and a screw nut arranged on the rear end of said upper shaft and engaging with the rear end of said sleeve.

3. A metal working machine comprising 125 an enclosing casing provided in the lower part of its front and rear walls with fixed bearings, a front opening in the upper part of its front wall having vertical guideways on its opposite sides, a rear opening in the 130

upper part of its rear wall, and a side opening in one of its side walls, a vertically movable slide arranged in said front opening and guided in said ways and provided with an upper front bearing, a sleeve arranged in said upper rear opening and provided with an upper rear bearing, pivots arranged on the rear wall and engaging opposite sides of said sleeve, a lower shaft journaled in said lower bearings and extending through said casing, an upper shaft extending through said upper front and rear bearings and extending through said casing, upper and lower intermeshing gear wheels arranged within the casing and secured to said upper and lower shafts, respectively; co-operating rolls mounted on the front ends of said shafts outside of said casing, means for vertically adjusting the front end of said upper shaft, a spring interposed between said upper gear wheel and said sleeve, and a screw nut arranged on the upper shaft and engaging with the rear end of said sleeve.

In testimony whereof I hereby affix my signature.

FREDERICK E. MUNSCHAUER.
